UNITED STATES PATENT OFFICE

97,187

DESIGN FOR A BURIAL CASKET

Hans P. Hansen, Syracuse, N. Y., assignor to
Marsellus Casket Company, Syracuse, N. Y., a
corporation of New York

Application August 30, 1935, Serial No. 58,378

Term of patent 7 years

To all whom it may concern:

Be it known that I, Hans P. Hansen, a citizen of the United States of America, residing at Syracuse, in the county of Onondaga and State of New York, have invented a new, original, and ornamental Design for a Burial Casket, of which the following is a specification, reference being had to the accompanying drawing, forming part thereof.

Figure 1 is a perspective view of a burial casket showing my new design;

Figure 2 is a fragmentary end elevation of one of the four similar corners of my casket;

Figure 3 is a fragmentary side elevation of the corner shown in Figure 2;

Figure 4 is a diagonal vertical sectional view through the corner taken on the line 4—4, of Figure 5;

Figure 5 is a horizontal sectional view taken on the line 5—5 of Figure 2; and

Figure 6 is a horizontal sectional view taken on the line 6—6 of Figure 2.

The characteristic features of the design are the slanting side and end walls of the casket body between the top and bottom moldings, and the merging of these walls into a corner which is square at the top and rounded at the bottom, as best illustrated in Figures 2, 3, 5 and 6, and providing a vertical line at the intersection of the outer faces of the side and end walls, as shown more clearly in Figures 4, 5 and 6. Subsidiary features are having the top molding square at the corner and the bottom molding rounded, to match the contours of the adjacent portions of the side and end walls.

I claim:

The ornamental design for a burial casket substantially as shown and described.

HANS P. HANSEN.
